OCCULTER FOR SEARCHLIGHTS

Charles Edward Cleuston, Isleworth, England, assignor to Sperry Gyroscope Company, Inc., Brooklyn, N. Y., a corporation of New York

Application June 17, 1937, Serial No. 148,655
In Great Britain June 26, 1936

9 Claims. (Cl. 177—329)

This invention relates to occulters for searchlights, particularly for those employing electric arcs.

When a searchlight is extinguished the carbons—or the incandescent lamp filaments if used—continue to glow for some little time with the result that the searchlight continues to be visible. This is inconvenient in war conditions or when the searchlight is being used for signaling. To overcome this disadvantage it is already known to provide means so that, when the current is switched off or the arc is broken, the residual light from the still glowing source is intercepted. Such means are known as occulters.

It is also known to provide means whereby the occulter is moved automatically into the occulting position when the current is cut off or the arc is broken, and is moved automatically into a non-occulting position when the supply is switched on or the arc is struck.

The design of an occulter is a matter of some difficulty. It has been proposed to provide shutters across the front of the usual searchlight casing or drum but either these are large and expensive in construction and operation, or they are unreliable, or slow in action, or they obstruct a considerable amount of light in the non-occulting position and so reduce the beam candle power available. Usually they suffer from several if not all, of these disadvantages. Moreover the searchlight drum has to be specially designed for them, whereas it is desirable that the lamp and mechanism should be capable of being used in a standard projector.

It has also been proposed to provide a small occulter for arc lamps which should move up and almost totally enclose the glowing carbons in the occulting position, so as to cut off practically all the light. During operation of the light, such occulters were moved into a non-occulting position for which a position in the shadow of the fixed parts of the lamp was selected, so that the occulter should not intercept any more light than was necessarily already obstructed in any case. These requirements, together with that of avoiding the operating mechanism, involved the necessity for the occulter to move a considerable distance, and this made it slow in operation, or liable to damage. On the other hand, since the occulter had to be small and yet to enclose the glowing carbons closely, it was liable to become burned or to give rise to short circuits or to interfere with rapid arc striking. The fact that the heat was totally enclosed naturally increased the danger of burning.

Searchlights are usually provided with a reflector or mirror for the purpose of greatly increasing the beam candle power. When the light is extinguished, the mirror greatly increases the beam candle power from the residual glow, and it is this that makes the searchlight still visible. To provide an efficient occulter, it is therefore only necessary to intercept light from the source to the mirror and the interception of the direct light from the source is relatively unimportant. Some of this direct light is intercepted in any case by the fixed parts of the lamp and the amount intercepted may be increased by fixed screens not moving with the occulter.

According to the present invention an occulter is provided comprising one or more screening surfaces so shaped and positioned that in the non-occulting position they lie substantially parallel to the axis of the lamp, and therefore edge on to the light proceeding from the reflector or mirror. According to the invention also, the screening surface is movable into an occulting position in which it intercepts the light proceeding from the carbons to the reflector or mirror. Additional fixed screens may or may not be provided to cut off some or all of the direct light from the carbons.

The invention enables situations to be used for the non-occulting position of the occulting surfaces that could not be used in the prior art. Previously, as has been mentioned, situations were sought in the shadow of existing parts: as a result of the present invention situations in the lamp casing or drum remote from all operating parts of the lamp can now be used as the non-occulting or open position of the occulter. This simple lamp design, allows larger occulting surfaces to be used, thus promoting cooling, and also allows a short occulter movement to be employed, i. e. allows the occulting and non-occulting positions to be relatively near each other. From this last consequence it follows that the occulter may be operated quite rapidly.

According to my preferred construction a single movable occulting member is employed, pivotable about a horizontal axis so that it moves from an occulting position between the carbons and the reflector or mirror into a non-occulting position above the positive carbon and clear of the tail flame. In this construction the movable occulting member is preferably of the form of a plate with two side walls or else in the form of a part of a cylinder. In the occulting position this member closes over fixed screens and thereby forms a box totally enclosing the arc. Interen-

gaging flanges may be provided on the fixed and moving members so as to make the box light-tight. A further feature of this construction is that the fixed screen may be constructed as an open box casting solidly connected to both the positive and negative heads of the lamp, the positive and negative carbons both passing through the sides of this box. This construction allows a perfect light seal to be obtained.

10 The invention will now be described more fully with reference to the accompanying drawings in which

Fig. 1 is a side elevation of a form of the occulter comprising a single movable member swingable about a horizontal axis. The occulter is shown both in the open and closed positions relative to the parts of the lamp with which it co-operates.

Fig. 2 is a perspective view of the movable occulting member of the occulter shown in Fig. 1.

Fig. 3 is a perspective view of the fixed member with which the movable occulting member of Fig. 2 co-operates to form a light-tight box when the movable member is in the closed position.

25 Referring to the construction of occulter shown in Figures 1, 2 and 3, the single movable occulting member employed is in the form of a plate 23 with side walls 24 and 25: the plate 23 is shown as a flat plate, but could equally well be in the form of a half cylinder. The edges 26 of the side walls 24 and 25 and plate 23 are bent over so as to form a continuous groove 26 around three edges of the occulting member, Fig. 2.

In the occulting position (shown in full lines 35 in Figure 1) the occulting member fits (like a hood) over a fixed V-shaped member 27 in the manner shown in Fig. 1 whereupon a projecting edge portion 28 formed on the vertical limb of the fixed member engages in the groove 26 of the movable member. A groove 29 is formed around the edge of the inclined limb of the fixed member 27 and in the occulting position of the movable member the edge 30 thereof engages in this groove. The grooves 26 and 29 in the movable 45 and fixed members respectively may be lined with soft material, e. g. asbestos packing to form a bedding in which the edges 28 and 30 may rest, thus promoting light-tightness.

In Fig. 1 the movable member of the occulter 50 is shown in the occulting position in full lines and in the open or non-occulting position in broken lines, both in relation to an arc lamp. In this figure the reference numeral 31 indicates the positive carbon, 32 is the negative carbon, 33 55 is the positive nose cap and 34 is the negative nose cap. Both nose caps are shown as being of fabricated construction but could equally well be castings. They are supported by, but insulated from, the fixed member 27 of the occulter. In 60 this form of lamp, both nose caps become red hot in use and it is necessary to screen them. We therefore enclose them by annular projections 35 and 36 forming parts of the fixed member 27. As a further precaution an annular recess 37 is 65 formed in the negative carbon jaws 38 and 39 and encloses the lower end of the nose cap 34 and of the annulus 36. A similar recess could equally well be made in the positive carbon jaws.

The movable occulting member is carried by 70 arms 40 which are attached to a shaft 41 by means of the flanged bosses 42. A lever 43 is also attached to the shaft 41 for the purpose of rocking it, the lever being linked by the bar 44 to a solenoid in the base of the lamp or other known 75 means for operating the occulter. The shaft 41 is

journalled in a bearing or bearings forming part of the bracket 45.

The occulter may also be linked with an arc-striking electrode 46 which may be carried inside the fixed member 27 of the occulter or in a recess formed in part of the positive head. This arc striker, which is electrically connected to the positive carbon, is shown as being carried on the shaft 47 journalled in bearings 51 (Fig. 3) formed in the fixed member 27 of the occulter. 10 To the shaft 47 is secured a lever 48 which is coupled by the link 49 to a similar lever 50 fastened to the shaft 41. The arrangement of these levers and links is such that when the shaft 41 is turned by the turning means provided in the base, it causes the occulter to move from the closed position as shown in full lines to the open position as shown in broken lines and at the same time causes the arc-striking electrode 46 15 to move from a position in contact with the negative carbon 32 to a position under the positive carbon 31 thus causing in well-known manner an arc to be struck between the negative and positive carbons 32 and 31.

This construction solves the problem of combining arc-striking and occulting without allowing light leakage by a novel principle which is to put the movable arc-striking electrode permanently inside the limits of the enclosed box formed by the occulter in its closed position. 25

It will be noticed also that the conception of this occulter is radically different from that of the prior art. Whereas in earlier constructions the occulter comprised one or more movable parts which were additional to the main structure of the lamp and had to close over the carbons and adjacent parts to cut off light as best they could, the present structure comprises a more or less closed V-shaped box having a movable lid, (to which are attached the sides of the box in the 30 form shown).

The fixed box is incorporated as part of the lamp structure and is given as complicated form as may be necessary to enclose the carbons, nose-caps, and any other parts from which light may issue. It is clear from Fig. 1 that light-tightness, against light coming from the glowing carbons and nose-caps, not only indirectly but also by reflection from the parts of the lamp, may be obtained by this type of construction of a totally 45 different order from anything possible with two or more moving occulting members that have to avoid existing parts of the lamp in their movements.

What I claim is:

1. A searchlight occulting device comprising the combination with a housing enclosing the electrode tips on at least two sides, a movable screening member swingable vertically about a horizontal axis from the occulting to the non-occulting position and so shaped that in its occulting position it encloses said tips on all other sides and in its non-occulting position its screening surface lies substantially edge-on to the beam reflected by the searchlight. 55

2. A searchlight occulting device comprising a movable screening member, swingable vertically about a horizontal axis from the occulting to the non-occulting position and so shaped that in its non-occulting position its screening surface lies substantially edge-on to the beam reflected by the searchlight, and a fixed occulting member co-operating with the movable member. 60

3. The combination with a searchlight comprising a substantially horizontal positive carbon and 70

an inclined carbon, operating mechanism there-
for, reflecting means and a lamp casing, of an
occulting mechanism comprising a fixed mem-
ber and a movable member, the fixed member
5 being in the form of a V-shaped plate having one
limb located as a vertical screen through which
the positive carbon projects and the other limb
located as an inclined screen through which the
negative carbon projects, and the movable mem-
10 ber being a hood shaped plate which in the non-
occulting position lies with its screening surface
substantially edge-on to the reflected beam and
in its occulting position fits hood-like over the
fixed member to constitute a substantially closed
15 box around the ends of the carbons.

4. The combination of a searchlight and occult-
ing mechanism according to claim 5, the co-oper-
ating edges of the fixed occulting member and
20 the movable occulting member being inter-fitting
in relation to one another to ensure light-
tightness.

5. The combination of a searchlight and occult-
ing mechanism according to claim 3 the portions
25 of the V-shaped plate of the fixed occulting mem-
ber through which the carbons project being
formed as annular projections circumferentially
surrounding said carbons.

6. A searchlight occulting device comprising
movable occulting means of sheet form which in
30 the non-occulting position lie with the screening

surface substantially edge-on to the searchlight
beam, and an arc-striking electrode located inside
the limits of the occulting device when in the
occulting condition.

7. A searchlight occulting device according to
claim 6, including a single means for actuating
the occulter and for actuating the arc-striking
electrode.

8. A searchlight occulting device comprising the
combination with a housing enclosing the elec-
10 trode tips on at least two sides, a single movable
screening member swingable about an axis lo-
cated to one side of said tips from the occulting
to the non-occulting position and so shaped that
in its occulting position it encloses said tips on
15 all other sides and in its non-occulting position
its screening surface lies substantially edge-on to
the beam reflected by the searchlight.

9. In a combined occulting and arc striking
device for searchlights, the combination with
10 electrode holders enclosing the arcing tips on at
least two sides, an occulting means of sheet
form which in the occulting position encloses the
said tips on their other sides, a movable arc
striking electrode within the enclosure formed by
25 said occulting means and movable from one elec-
trode to the other, said arc striking electrode
being at all times located within the overall
dimensions of said enclosure.

CHARLES EDWARD CLOUSTON. 20
